(57) **CLAIM**

The ornamental design for blower casing, as shown and described.

DESCRIPTION

FIG. 1 is a perspective view of the blower casing in accordance with the claimed design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof wherein the broken lines define portions of the blower casing that form no part of the claimed design.
